CLAIM

The ornamental design for a shoe sole, as shown and described.

DESCRIPTION

FIG. 1 is a bottom, left, and rear isometric view of an ornamental design for a shoe sole;

FIG. 2 is a front elevational view of the shoe sole of FIG. 1; FIG. 3 is a rear elevational view of the shoe sole of FIG. 1; FIG. 4 is a right side elevational view of the shoe sole of FIG. 1;

FIG. 5 is a left side elevational view of the shoe sole of FIG. 1;

FIG. 6 is a top plan view of the shoe sole of FIG. 1; and, FIG. 7 is a bottom plan view of the shoe sole of FIG. 1. The drawings include grayscale surface shading which illustrates contour, not any particular color.

1 Claim, 7 Drawing Sheets
